UNITED STATES PATENT OFFICE.

JOSEPH CHARY, OF OBERHOMBURG, LOTHRINGEN, GERMANY.

BUCKLE.

1,138,540.

Specification of Letters Patent.

Patented May 4, 1915.

Application filed August 6, 1914. Serial No. 855,466.

To all whom it may concern:

Be it known that I, JOSEPH CHARY, a subject of the Emperor of Germany, residing in Oberhomburg, Lothringen, Germany, have 5 invented certain new and useful Improvements in Buckles, of which the following is a specification.

This invention relates to an improved buckle of the kind in which the buckle 10 tongue or spiked member is arranged to glide in stationary parts of the buckle frame proper. According to this invention and in contra-distinction to known buckle constructions of this class the shanks of the 15 spiked member are prolonged to the rear so as to diverge and to form together a loop-shaped handle by means of which the spiked member may be actuated and which at the same time serves for the insertion of the end 20 of the strap on which the buckle is used. The spike-shaped shanks, moreover, are guided in stationary transverse members of the buckle frame so as to be capable of a limited gliding movement therein and to this 25 end are provided with stops or abutments between the stationary members and preferably also with outwardly curved ends between the abutments and the handle thereof, as will hereinafter be more clearly seen 30 with reference to the accompanying drawings forming part of this specification and in which:

Figure 1 shows a plan view of my improved buckle with the spiked member in 35 open or drawn out position. Fig. 2 is the same buckle showing the buckle frame attached to a strap and the spiked member in drawn out position. Fig. 3 shows the arrangement of Fig. 2 with the spiked member in closed or forward position. Fig. 4 shows the buckle with the spiked member 40 closed with both ends of the strap connected thereby. Fig. 5 shows a lateral view of Fig. 1, and Fig. 6 shows in detail one of the stationary transverse members in which the 45 spiked shanks of the buckle are guided.

As shown in the drawing, the buckle according to my invention consists of the buckle frame *a* which may be of metal and 50 of any desired shape or construction. Arranged between the longitudinal members

of this frame *a* are two transverse members 55 *b* preferably of the construction shown in Fig. 6. These transverse members are immovably secured to or are integral with the buckle frame *a* and are provided with eye pieces *c*. These eye pieces are adapted to 60 receive and to guide the spiked shanks *c* of the tongue or spiked members *d* so that the latter may be slid in forward or backward direction within the buckle frame. The shanks *c* are prolonged rearwardly in a 65 diverging manner and the extreme points of the diverging portions *c'* are connected together to form a loop-shaped handle *e* by means of which the spiked member may be readily operated. The loop *e*, as shown, is 70 preferably gradually offset upwardly and is of such dimension as to accommodate the closing end *s'* of the strap *s* when the spiked member has been forced home to penetrate this end of the strap as shown in Fig. 4. 75 Integral with or securely connected to each spike *c* within the transverse guides *b* is an abutment or stop *f* by means of which both the forward and rearward movement of the spiked member is automatically limited 80 between the stationary guides *b*, as will be readily understood. In addition to these stops the shanks *c* may be provided with outwardly curved portions *h* which aid the limiting action of the stops *f* and at the 85 same time provide for a resilient working of the spiked member within its guides.

What I claim and desire to secure by Letters Patent is:—

In a buckle, the combination of a buckle 90 frame, stationary transverse members extending across the buckle frame and provided with eye pieces, a spiked member having its spikes guided in the said eye pieces and provided with stops between the said 95 stationary members and with an upwardly curved loop-shaped handle for the accommodation of the end of the strap, substantially as set forth.

In testimony whereof I have affixed my 100 signature in presence of two witnesses.

JOSEPH CHARY.

Witnesses:

MARGARETE CHARY GEB. VON KIENLE,
PETER MÜLLER.
